Des. 179,001
Patented Oct. 23, 1956

179,001

PULL FOR DRAWERS, CABINET DOORS, AND THE LIKE

Don Heyer, El Monte, Calif.

Application November 8, 1954, Serial No. 33,029

Term of patent 14 years

(Cl. D10—8)

Fig. 1.

Fig. 2.

Fig. 3.

Fig. 4.

Fig. 1 is a perspective view of a pull for drawers, cabinet doors, and the like, showing my new design;

Fig. 2 is an edge elevation thereof as viewed from the left of Fig. 1;

Fig. 3 is a front elevation thereof, and

Fig. 4 is a rear elevation thereof.

I claim:

The ornamental design for a pull for drawers, cabinet doors, and the like, as shown.
